HAIR CURLING APPLIANCE

Doriane Archer, Los Angeles, Calif.

Application March 8, 1941, Serial No. 382,403

9 Claims. (Cl. 132—41)

This invention relates to a device or appliance for curling hair and it is a general object of the invention to provide a simple, practical and very effective hair curling appliance of the type on which a strand of hair is wound to remain in a wound or curled state for a substantial period or until it retains the desired curled contour.

Another object of this invention is to provide a hair curling device of the character referred to embodying particularly dependable means for maintaining the hair strand wound on the spindle element.

Another object of this invention is to provide a hair curling appliance of the character referred to that is compact and inconspicuous and easy and convenient to use.

Another and important object of the invention is to provide a hair curler of the character mentioned that is very simple in construction and inexpensive of manufacture, embodying a minimum number of parts.

A further object of this invention is to provide a hair curling appliance of the character referred to that is devoid of pins, sharp edges and other hazardous parts, and that will not cut, break or tangle the hair.

The various objects and features of my invention will be fully understood from the following detailed description of typical preferred forms and applications of my invention, throughout which description reference is made to the accompanying drawing, in which:

Fig. 1 is an elevation view of one form of the invention in the extended condition illustrating the manner in which the end of a hair strand is engaged in the spindle. Fig. 2 is a view similar to Fig. 1 with the strand wound on the spindle. Fig. 3 is a side or edge elevation of the device with the keeper in the active position holding the strand wound on the spindle. Fig. 4 is a perspective view of the device showing one section of the keeper raised and Fig. 5 is a view similar to Fig. 4 illustrating a slightly modified form of the invention.

The form of the invention illustrated in Figs. 1 to 4, inclusive, of the drawing may be said to comprise, generally, a spindle 10 on which the hair strand S is to be wound, and a keeper 11 carrying the spindle 10 and operable to maintain the strand S curled or wound on the spindle.

The spindle 10 forms the shaft or mandrel of the appliance for receiving the wound hair strand S. In the preferred construction the spindle 10 is a simple structure formed to grip or receive the end portion of the strand S to facilitate winding

of the strand. As illustrated in Figs. 1 to 4, inclusive, of the drawing, the spindle 10 comprises two elongate tines, fingers or arms 12 and 13. The arms 12 and 13 are of substantially the same length and width and are arranged in generally parallel face to face relation. The arm 12, which I will term the lower arm, is a straight, flat strip, while the arm 13 has a downwardly stepped or offset portion 14 at its inner end which bears or rests on the opposing face of the arm 12. This spaces the major portion of the arm 13 from the arm 12 leaving a gap or slot to receive the end portion of the hair strand S. The outer ends of the arms 12 and 13 may be rounded off, as illustrated. It is preferred to make the outer sides of the spindle arms 12 and 13 convex or substantially cylindrically curved so that the two arms form a substantially cylindrical shaft or spindle to give the wound hair strand S the desired form. The inner sides of the arms 12 and 13 may be flat and substantially parallel. The extreme end portions of the spindle arms 12 and 13, which do not receive the hair strand S, may have flat outer surfaces.

The keeper 11 forms a carrier for the spindle 10 and serves to hold the hair strand S wound on the spindle and thus serves to hold the device on the hair. In the construction of Figs. 1 to 4, inclusive, of the drawing, the keeper 11 embodies two hingedly connected sections 15 and 16. The sections 15 and 16 are elongate strap-like parts of substantially the same length which may have straight parallel longitudinal edges. The keeper sections 15 and 16 are connected in end to end relation by a hinge 17 comprised of a pin 18 passing through meshing rolled on tubular lugs on the adjoining ends of the sections 15 and 16. The ends of the hinge pin 18 are riveted or rounded over to prevent displacement of the pin and to remove sharp edges.

The keeper section 15, which I will term the lower section, is shaped or bent to have a raised platform portion 19 at one end for supporting the spindle 10. The inner end portion of the lower spindle arm 12 rests on the platform portion 19. A pivot pin 20 is arranged through transverse openings in the platform portion 19, the lower spindle arm 12 and the upper spindle arm portion 13 to pivotally connect the spindle 10 with the keeper 11. The ends of the pin 20 are riveted or headed up to prevent disconnection of the parts and to remove sharp edges. It will be observed that the platform portion 19 of the keeper section 15 supports the spindle 10 so that the lower spindle arm 12 is spaced from the

major portion of the keeper section 15 leaving a space for the reception of the curled or wound hair strand S.

The upper or outer section 16 of the keeper 11 is initially or normally a substantially straight elongate part. The keeper section 16 is adapted to overlie the spindle arm 13 and to engage against the wound hair strand S. The keeper sections 15 and 16 are constructed of flexible resilient material to be bowed or flexed outwardly through contact with the roller strand S when in the active positions illustrated in Fig. 3. The free or outer end of the keeper section 16 is releasably connected or latched with the platform portion 19 to hold the keeper in its active position.

The outer end portion of the keeper section 16 is shaped to form a spring catch 21. The latch portion or catch 21 is an integral part of the section 16, the end portion of the section 16 being curved downwardly and rearwardly and then pitched downwardly and outwardly to form the catch 21. When the spindle 10 is between the keeper sections 15 and 16 with the strand S wound thereon, the keeper sections 15 and 16 may be brought together so that the catch 21 engages under or latches with the platform 19. This retains the keeper 11 in its active position. As illustrated in Fig. 3 of the drawing the keeper sections 15 and 16 are curved or bowed through contact with the wound hair strand S and the resiliency of the bowed sections maintains the catch 21 in effective holding engagement with the platform portion 19. Direct manual manipulation may free the catch 21 from the platform 19 or the sections 15 and 16 may be subjected to a compressive force to free the catch 21 from the platform 19.

Fig. 5 of the drawing illustrates an alternative or modified form of the invention in which the spindle 10^a differs from the above described spindle 10 in being a one-piece or integral member. In this structure the spindle 10^a comprises two arms 12^a and 13^a similar to or identical with the arms 12 and 13, respectively, but integrally joined at their inner ends. The spindle 10^a may be constructed of a single length of material of the desired width and thickness bent back upon itself and shaped to have the offset portion 14^a and to have the two arms 12^a and 13^a.

The structure illustrated in Fig. 5 of the drawing is further characterized by an integral or one piece keeper 11^a. The keeper 11^a is constructed from a single strip or length of material of the desired width and thickness and possessing the required flexibility and resiliency. This length of material is shaped or bent to normally be substantially V-shaped having arms or parts 15^a and 16^a corresponding to the sections 15 and 16 and connected by an apex portion or connecting portion 25. The part 15^a is provided with a platform 19^a corresponding to the above described platform 19 and the outer end of the part 16^a has a catch 21^a corresponding to the catch 21. The hair curler shown in Fig. 5 operates in the same manner as the curler illustrated in Figs. 1 to 4, inclusive.

In both of the above described forms or embodiments of the invention the spindle and the keeper may be formed of metal, pyroxylin, plastic material, paper, fibrous materials or other materials possessing the required flexibility and resiliency. Further, the parts may be plated or ornamented as desired and may be of any selected color or colors.

Referring now to Figs. 1 to 4, inclusive, of the drawing, the spindle 10 is swung or hinged from the keeper 11 and the keeper sections 15 and 16 are hinged to the extended positions so that the parts are as shown in Fig. 1. With the parts in this condition the end portion of the hair strand S may be easily engaged between the spindle arms 12 and 13. In this connection it is to be understood that the spacing of the spindle arms 12 and 13 may be such that the arms grip the hair strand S with a suitable pressure. With the end of the strand S engaged in the spindle 10 the spindle is turned or rotated to wind the hair strand thereon. In carrying on this operation it is usually preferred to have the spindle 10 extend laterally from the keeper 11, as shown in Figs. 1 and 2 and, if desired, the keeper either extended or with its sections 15 and 16 together may be employed as a crank or handle for turning the spindle.

With the hair S wound on the spindle 10, the spindle 10 and the keeper 11 are pivoted with respect to one another to bring the spindle to the position where it is within or substantially parallel with the keeper. The keeper sections 15 and 16 are then pivoted or swung toward one another, for example, they may be pressed between the thumb and first finger to engage the catch 21 with the platform 19. This latches the keeper 11 in its active position. The keeper 11 securely engaged against the opposite sides of the wound hair strand S dependably retains the strand in its wound condition and holds the device in place. When it is desired to remove the device or appliance the catch 21 is released from the platform 19, as described above, and the spindle 10 is freed or withdrawn from the wound hair strand S.

Having described only typical preferred forms and applications of my invention, I do not wish to be limited or restricted to the specific details herein set forth, but wish to reserve to myself any variations or modifications that may appear to those skilled in the art, or fall within the scope of the following claims.

Having described my invention, I claim:

1. A hair curler comprising a keeper including two parts connected at their inner ends to be movable toward and away from one another, a spindle secured to the inner side of one keeper part adjacent the outer end of the same on which a strand of hair may be wound, and releasable means for connecting the outer ends of the keeper parts when the same are moved toward one another so that the parts hold the strand in the wound condition.

2. A hair curler comprising a keeper including two elongate parts connected at their inner ends for movement toward and away from one another, a spindle on which a strand of hair is to be wound, means pivotally supporting the spindle on the outer end of one keeper part to be swingable from an extended position to a position between said parts, and means for connecting the outer ends of the keeper parts to hold the parts in cooperation with the wound strand to prevent unwinding of the same.

3. A hair curler comprising a keeper including two elongate parts connected at their inner ends for movement toward and away from one another, a spindle on which a strand of hair is to be wound, means pivotally supporting the spindle on the outer end of one keeper part to be swingable from an extended position to a position between said parts, and means for con-

necting the outer ends of the keeper parts to hold the parts in cooperation with the wound strand to prevent unwinding of the same, the last named means including a spring catch on one part for latching with the other part.

4. A hair curler comprising a keeper including two elongate parts connected at their inner ends for movement toward and away from one another, a platform on the outer end of one part, an elongate spindle on which a strand of hair is to be wound, the spindle being divided to receive the end of the strand, means pivotally supporting an end of the spindle on the platform to be swingable from a laterally projecting position to a position between the keeper parts, and latch means for releasably connecting the outer ends of the keeper parts so that the parts retain the wound strand on the spindle.

5. A hair curler comprising a keeper including two elongate parts connected at their inner ends for movement toward and away from one another, a spindle on which a strand of hair is to be wound, means pivotally supporting the spindle on the outer end of one keeper part to be swingable from an extended position to a position between said parts, and means for connecting the outer ends of the keeper parts to hold the parts in cooperation with the wound strand to prevent unwinding of the same, the last named means comprising a spring catch on the outer end of one part for latching with the other part to hold the parts pressed against the wound strand so that the parts are bowed outwardly through contact with the wound strand and releasable by inward flexure of the parts.

6. A hair curler comprising a one-piece keeper including two elongate parts connected at their inner ends for movement toward and away from one another, a spindle on which a strand of hair is to be wound, means pivotally supporting the spindle on the outer end of one keeper part to be swingable from an extended position to a position between said parts, and means for connecting the outer ends of the keeper parts to hold the parts in cooperation with the wound strand to prevent unwinding of the same.

7. A hair curler comprising a keeper including two elongate sections, and means hingedly connecting the inner ends of the sections so that the sections may be opened and closed, a spindle on which a strand of hair is to be wound, means supporting the spindle on the outer end of a keeper section to be swingable between a position projecting laterally from the keeper and a position between the sections of the keeper, and a catch on the outer end of a keeper section for cooperating with the other keeper section to hold the sections against the wound strand to prevent unwinding of the same.

8. A hair curler comprising a keeper including two elongate sections, and hinge means connecting the inner ends of the sections so that the sections may be opened and closed, a spindle on which a strand of hair is to be wound, the spindle comprising a pair of arm members in side by side relation, means supporting the spindle on the outer end of a keeper section to swing about an axis transverse of the axis of said hinge so that the spindle may be moved; between a position projecting laterally from the keeper and a position between the sections of the keeper, and a catch on the outer end of a keeper section for cooperating with the other keeper section to hold the sections against the wound strand to prevent unwinding of the same.

9. A hair curler comprising a keeper including two elongate parts connected at their inner ends for movement toward and away from one another, a spindle on which a strand of hair is to be wound, the spindle comprising an integral elongate member bent back upon itself to have two arms between which the strand may be engaged, means pivotally supporting the spindle on the outer end of one keeper part to be swingable from an extended position to a position between said parts, and means for connecting the outer ends of the keeper parts to hold the parts in cooperation with the wound strand to prevent unwinding of the same.

DORIANE ARCHER.
